UNITED STATES PATENT OFFICE.

EDWIN S. GILES, OF FENTON, MICHIGAN, ASSIGNEE TO A. M. BENTLEY, OF OWOSSO, MICHIGAN.

WINDOW-SCREEN.

SPECIFICATION forming part of Letters Patent No. 738,899, dated September 15, 1903.

Application filed May 18, 1903. Serial No. 157,510. (No model.)

To all whom it may concern:

Be it known that I, EDWIN S. GILES, a citizen of the United States, residing at Fenton, county of Genesee, State of Michigan, have 5 invented a certain new and useful Improvement in Window-Screens, of which the following is a specification, reference being had to the accompanying drawings, which form a part of this specification.

10 My invention has for its object certain new and useful improvements in window-screens; and it consists of the mechanism hereinafter described and claimed, and illustrated in the accompanying drawings, in which—

15 Figure 1 is a view in perspective showing a screen-frame in expanded position embodying my invention. Fig. 2 is a view in perspective showing portions of the frames, the frames being broken away to more fully illustrate the invention. Fig. 3 is an edge view of the frames shown in a partially-closed position. Fig. 4 is a detail view of the clasp. Fig. 5 is a view in transverse section through the frames as on the line 5 5, Fig. 3.

20 The aim of my invention is to provide adjustable screen-frames, the same being of simple and economical construction and efficient in their operation.

In the accompanying drawings, *a a* represent 30 two companion frames, each constructed with two side rails and a connecting end rail. To each of these frames is attached wire netting or gauze (indicated at *b b*) provided at their adjacent ends with a metal binding, (indicated at *c c*.) The said rails of each of the frames on the opposite or outer surfaces thereof are constructed with longitudinal grooves, (indicated at *d d*.) Metal clasps are indicated at *e*, constructed as shown 35 in detail in Fig. 4. The clasps are each bent intermediate the lateral edges thereof to form side flanges, (indicated by the numerals 1 and 2), said side flanges 1 and 2 terminating with inwardly-turned flanges 3 and 4, the 40 inwardly-turned flanges 3 and 4 entering the recesses *d d* of the companion frames, as shown. The intermediate or body portion of the clasp extends over the adjacent edges of both the frames *a a* and is secured in any

suitable manner to one of said frames. This 50 may be done simply by indenting the body portion of the clasp into one of the frames, as indicated at *f*, or the clasp may have a fixed engagement with one of the frames in any suitable manner, so that the clasp will be 55 held rigid upon one of the frames, while the other frame has a movable or adjustable engagement therewith.

It will readily be seen that the two frames *a a* are held from lateral disengagement by 60 the clasps, and the clasps meeting one another when the two frames are expanded will prevent the frames from being longitudinally disengaged the one from the other. The clasps *e* serve thus to hold the two parts of 65 the frame together in a convenient manner. The engagement is such as is not liable to get out of order, nor are the frames liable to bind. The clasps are located at the inner ends of 70 the corresponding frames and are engaged upon the upper and lower rails of the frame.

What I claim as my invention is—

1. An adjustable window-screen comprising two frames constructed with longitudinal grooves on the outer faces of the upper and lower rails between the opposite edges thereof, said frames having in combination therewith metallic clasps attached to the inner ends of the upper and lower rails of the frames, and each having a sliding engagement with the 80 frame opposite that to which the clasp is attached, said clasps each constructed with flanges projecting from opposite edges thereof inwardly over the lateral face of the frame to which the clasp is attached and over the lateral face of the adjacent frame, said clasps provided with inwardly-turned marginal flanges projecting into the corresponding grooves of the frame, substantially as set forth. 85

2. An adjustable window-screen comprising two frames each having upper and lower rails grooved on the outer faces thereof, said rails each provided with a metallic clasp having a fixed engagement therewith and constructed with inwardly-projecting lateral flanges extending over the opposite faces of the adjacent rails and with inwardly-project- 95

ing marginal flanges entering into the adjacent grooves of the respective rails, the frame opposite that to which the clasps are rigidly attached having a movable engagement with 5 the corresponding clasps, the body of the clasps extending over the adjacent outer edges of the adjacent rails of the frame.

In testimony whereof I have signed this specification in the presence of two subscribing witnesses.

EDWIN S. GILES.
